Specification for Design.

Patented Mar. 15, 1921.

Application filed July 22, 1920. Serial No. 398,315. Term of patent 3½ years.

To all whom it may concern:

Be it known that I, MAX KLEIN, a citizen of the United States, and residing at New York, in the county of New York and State of New York, have invented a certain new, original, and ornamental Design for a Support for a Hall-Light, of which the following is a specification, reference being had to the accompanying drawing, forming part thereof.

The figure is a perspective view of a support for a hall light embodying my new design.

I claim:

The ornamental design for a support for a hall light as shown.

MAX KLEIN.
